IMPROVEMENT IN RAG ENGINES FOR PAPER MAKING.

JAMES M. SHEW, OF PAPER MILLS, MARYLAND.

Letters Patent No. 60,645, dated December 18, 1866.

The Schedule referred to in these Letters Patent and making part of the same.

TO ALL WHOM IT MAY CONCERN:

Be it known that I, JAMES M. SHEW, of Paper Mills, in the county of Baltimore, and State of Maryland, have invented a new and useful Improvement in Rag Engines for Paper Making; and I do hereby declare that the following is a full, clear, and exact description thereof, which will enable others skilled in the art to make and use the same, reference being had to the accompanying drawings, forming a part of this specification, in which—

Figure 1 is a vertical longitudinal section of a rag engine, taken in the line $x x$, fig. 2.

Figure 2 is a plan of the same.

Similar letters of reference indicate like parts.

This invention relates to an improvement on rag engines for the manufacture of paper, and consists in attaching to each end of the cutting cylinder a voluted flange or spiral scroll, for the purpose of preventing the rags from working in around the spindle and choking the cylinder, thus materially increasing friction and wasting power, as is the case with the ordinary rag engine. My improvement saves this loss of power, and as it prevents the passage of any of the rags through the engine except between the cutters, they are all equally comminuted and reduced to a perfectly even paper pulp. Except in my improvement, the rag engine is in all respects the same as those in ordinary use.

A represents the cistern or pulp vat; B, the cutting cylinder, hung on the spindle, C, above the rising incline, $a a$, and the falling incline $a' a'$; $b b$ are the cutters on the cylinder, and $c c$ the block plates or stationary cutters underneath the cylinder; D is the cap or box cover of the cylinder. On each end of the cutting cylinder, B, is placed a spiral scroll or voluted flange $e e$, the pole of which volute is the spindle C, to which it is united, terminating in its convolution at the periphery of the cylinder. The flange projects equally at both ends of the cutting cylinder, so as just to fill and clear the sides of the compartment in which it revolves, and the coil of the flange is in the same direction on both ends, the scroll or volute expanding or unrolling contrary to the line of rotary movement of the cylinder, indicated by the arrow, fig. 1, the effect of which arrangement is obviously to constantly throw off the pulp from the centre to the circumference, and prevent any accumulation of rags at the ends and around the spindle, D, when the cutting cylinder revolves.

Having thus described my invention, what I claim as new, and desire to secure by Letters Patent, is—

Placing a spiral scroll or voluted flange on the ends of the cutting cylinder of a rag engine of a paper mill, substantially as and for the purposes herein described.
